UNITED STATES PATENT OFFICE

CHARLES F. PIKE, OF PHILADELPHIA, PENNSYLVANIA.

ORE WASHER OR CONCENTRATOR.

SPECIFICATION forming part of Letters Patent No. 528,979, dated November 13, 1894.

Application filed June 10, 1893. Renewed April 17, 1894. Serial No. 507,944. (No model.)

To all whom it may concern:

Be it known that I, CHARLES F. PIKE, a citizen of the United States, residing at Philadelphia, in the county of Philadelphia and State 5 of Pennsylvania, have invented certain new and useful Improvements in Ore Washers or Concentrators; and I do hereby declare the following to be a full, clear, and exact description of the invention, such as will enable 10 others skilled in the art to which it appertains to make and use the same.

My invention has relation to that form of ore washers and concentrators wherein the ore is fed into the washer at one end or 15 side and then rotated to an opposite or distant discharge end or side which has heretofore mainly been done by rotating the vessel into which the ore is fed and from which it is discharged; and it has for its object to provide 20 a stationary washer and rotate both the feed and the discharge devices, the latter being in advance of the former, whereby the traveling or rotating feed device deposits or drops into the washer a continuous feed in 25 the path of its movement, and the traveling discharge correspondingly acts to discharge the waste-matter, not, however, of a feed being deposited, but of one previously deposited, so that ample time is afforded between the 30 interval of deposit and discharge for the metal in the ore or gangue to separate from the waste-matters before the latter are withdrawn from the washer.

My invention has for its further object to 35 so discharge the gangue from the washer that no free gold is mechanically carried up between stones, rock or other like substances through the discharge appliances.

My invention accordingly consists of a system 40 of washing and concentrating ore or gangue and of the combinations, constructions and arrangements of parts as hereininafter more fully described in the specification and pointed out in the claims.

Reference is had to the accompanying drawings, wherein—

Figure 1 is a sectional elevation of an ore washing and concentrating device embodying my improvements. Fig. 2 is a like view of part 45 of same showing a modified form of feed and discharge pipe ends for the washer. Fig. 3 is a plan of the greasy gold collector for the

washer. Fig. 4 is a sectional view of the inlet end of the suction pipe, showing it arranged to successively discharge the different grades 55 or bulk of material of which the gangue is composed. Fig. 5, is a plan partly sectional of another form of washer and Fig. 6 is an elevation of same.

A represents any suitable form of washer 60 or concentrator vessel suitably held or mounted in a fixed position, and B jarring mechanism for agitating and spreading the gangue supplied to it. Said mechanism may be of any suitable kind and located as the requirements of service demand. In the drawings it is shown composed of a reciprocating striker bar b actuated from a power crank b⁹ through the instrumentalities of links or other connections b², located opposite one side 65 of the vessel A while on the other side is provided a rubber or other elastic cushion c. Suitably suspended above the vessel A is an ore supply trough D receiving its supply of water and ore or the latter separately from a 70 revolving or other screen E.

From trough or receiver D leads the feed pipe F for supplying ore to the vessel A. The receiver D and pipe F are mounted on a discharge or suction pipe G so as to rotate therewith, and said pipe G has a socket joint connection g with the pump g' and is rotated by a belt or other power transmitting device g². Said pipes F and G are suitably configured to conform to their path of movement 75 in vessel A, and when rotated the feed pipe E discharges in the path of its movement a supply of ore in vessel A, see more plainly Fig. 2, to admit of the metal separating therefrom before coming within the influence of 80 the suction or discharge pipe G, or in other words the latter is located ahead of the supply pipe and discharges gangue which has been previously deposited by the feed pipe and in such respect said feed and discharge 85 while rotating together in close proximity are relatively distantly located in respect to the functions they perform. Hence there is a 90 clear space x (see Fig. 2) always between the feed and discharge, and to provide for collecting any free floating greasy gold or other 95 heavy metal not taken up by the discharge, a grate, reticulated, or perforated collector H is inserted between the feed and discharge. 100

In the drawings this collector is represented as attached to the feed pipe F and extending toward the suction pipe G.

To provide for withdrawal of first the 5 lighter particles of the gangue and then the gradually increasing heavier particles instead of withdrawing them all simultaneously, the end g^5 of the suction pipe may be made with a rising incline having its lowest 10 point nearest the feed pipe and gradually elevating as shown. Within said end are partitions g^6 to divide it into chutes or chambers $g^7 g^8 g^9$ which lead into the common pipe G, as shown more plainly in Fig. 4. The chute g^7 being highest from the surface or level of discharge in vessel A has the least suction power but is in advance of all the successive chutes which successively coming nearer to the said level of discharge have correspondingly increased suction power. The fine particles of the gangue are first withdrawn or discharged into tube G, then the next heavier particles and so on until the largest and heaviest particles that the pump will discharge are taken up. This system of discharge admits of the thorough successive separation of said particles. Hence the lighter or less heavy metal particles do not segregate with the bulky waste matters to be carried up 25 with them through the discharge pipe.

From the foregoing it will be noted that the feed deposited in the washer, is agitated therein and before being discharged all the free metal has ample opportunity to separate 30 itself from the gangue up to and within the act of the gangue being discharged, and that the operation is continuous. Hence the device is especially available for working large 35 bulks of ore economically and without loss of metal. The washer is provided with any 40 suitable form of overflow as desired.

It will be further noted that the foregoing improvements are available for a concentrator having a layer of mercury therein upon 45 which the ore is fed as well as for a washer and concentrator.

In this application I claim broadly the inclined suction-pipe discharge end having chutes of varying suction power, while in 50 current pending application Serial No. 477,166 the same is only claimed specifically in combination with other elements.

As it is evident that the novel features of my invention may be greatly changed without 55 departing from the spirit of the same I do not confine myself thereto as shown and described.

What I claim is—

1. In combination with an ore washer or 60 concentrator, of a traveling feed device and a

suction discharge device and actuating devices for said feed and discharge, substantially as set forth.

2. In combination with a stationary ore washer or concentrator vessel, of actuating 65 mechanism for jarring said vessel, a traveling feed device and a suction discharge device, and actuating devices for said feed and discharge, substantially as set forth.

3. In combination with an ore washer or 70 concentrator, a stationary vessel containing mercury, of mechanism for jarring said vessel, a rotating tubular feed device and a corresponding suction discharge device and actuating mechanism for said feed and discharge, as substantially set forth.

4. In combination with an ore washer or 75 concentrator vessel containing mercury, of a traveling feed device, suction discharge device and a collector for removing impure 80 metal floating on the surface of the mercury, substantially as set forth.

5. The combination with a washer or concentrator, a traveling feed and discharge, one in advance of the other, and the discharge 85 acting on successively the preceding depositions, substantially as set forth.

6. In an ore washer or concentrator, the combination of a receiving vessel, a rotating feed, discharge, and greasy or impure metal 90 collector, substantially as set forth.

7. In an ore washer, a discharge suction pipe, having its inlet end inclined from below upwardly and partitioned to provide chutes of varying suction power, substantially as set 95 forth.

8. In an ore washer or concentrator an inlet end suction pipe having chutes of varying discharge or suction power, substantially as 100 set forth.

9. In an ore washer and concentrator a feed pipe, a suction discharge pipe, and a collector H, attached to one or both said pipes, substantially as set forth.

10. In an ore washer and concentrator the 105 combination of a receiving vessel, means for jarring the same, and a rotating discharge and feed, substantially as set forth.

11. In an ore washer and concentrator the 110 combination of a receiving vessel, and a rotating feed and a discharge distantly located relatively to their performed functions, substantially as set forth.

In testimony whereof I affix my signature in presence of two witnesses.

CHARLES F. PIKE.
